UNITED STATES PATENT OFFICE.

ANKER PETERSEN, OF WINTHROP, MASSACHUSETTS.

SPINDLE DRIVE FOR WINDING MACHINES.

Application filed September 8, 1923. Serial No. 661,714.

To all whom it may concern:

Be it known that I, ANKER PETERSEN, a citizen of the United States of America, and resident of Winthrop, in the county of Suffolk and State of Massachusetts, have invented new and useful Improvements in Spindle Drives for Winding Machines, of which the following is a specification.

This invention pertains to yarn and thread winding machinery and relates more particularly to mechanism for driving and automatically stopping the winding spindle.

The principal object of the present invention is to provide high speed winding mechanism of simple design capable of winding thin and tender yarns and including automatic stop mechanism for stopping the winding spindle when the yarn mass has attained a predetermined size as well as when the yarn breaks or becomes unduly slack, the stop mechanism comprising detector devices so arranged that they do not impose an injurious strain upon the yarn.

In the accompanying drawings a preferred embodiment of the invention is illustrated by way of example, and in the drawings:

Fig. 1 is a fragmentary plan view of one end of a winding frame showing one element of winding mechanism constructed in accordance with the present invention;

Fig. 2 is a front elevation of the parts shown in Fig. 1;

Fig. 3 is a fragmentary end elevation from the left-hand end of the device as viewed in Fig. 1;

Fig. 4 is an end elevation from the right-hand end of the device as viewed in Fig. 1, certain parts being shown in section;

Fig. 5 is a fragmentary detail sectional view on the line 5—5 of Fig. 2; and

Fig. 6 is a vertical section on the line 6—6 of Fig. 2.

The numeral 1 indicates a table or support forming a part of a winding frame which may be of any desired length and which may support any desired number of the winding units of which one is herein shown and described in detail. A shaft 1^a is journaled beneath the table 1 extending longitudinally of the latter and is provided with a driving drum or series of pulleys such as that shown at 1^b.

Each winding unit comprises a frame 2 having spaced standards 2^a provided at their upper ends with bearings 3 and 4 respec-

tively. A winding spindle S is mounted in journals in the bearings 3 and 4 and carries a fast pulley 5 and a loose pulley 6, the pulleys preferably being disposed between the bearings 3 and 4. The spindle S projects to the right of the bearing 4 as viewed in Fig. 2 and is provided with a face plate 7 having a central journal opening and a projecting dog 8.

A support 9 is pivotally connected at 10 to the frame 2 and is provided with a bearing 11 having a central journal opening opposed to the opening at the center of the face plate 7. The support 9 is furnished with a stop 12 for limiting its movement toward the face plate and is held in normal position by means of a spring 13. A second stop 14 may be provided for limiting the outward swing of the support 9.

As herein illustrated a spool 15 of the type commonly used in the carriers of braiding machines is mounted between the face plate 7 and the bearing 11. This spool is furnished with axial shaft projections 16 and 17 which engage the openings in the face plate 7 and in the bearing 11 respectively. One end of the spool is furnished with an opening or slot for the reception of the dog 8. While as here shown the mechanism is arranged for winding upon a spool having shaft projections 16 and 17, it is contemplated that the thread mass may be wound directly upon an extension of the spindle itself or upon a tube, spool or other device mounted upon such extension, the term "spindle" as herein employed being intended to include the spindle proper as well as any axial extension, integral or otherwise, thereof, as for example the spool here- in illustrated.

A driving belt 18 normally engages the fast pulley 5 and receives its motion from the driving pulley or drum 1^b. The belt or power transmitter 18 may be shifted to and from the loose pulley 6 by means of a belt shifter pivoted at 19 upon the frame 2. This belt shifter preferably consists of a bell crank lever having the upwardly extending arm 20 provided with hook like ears 21 and 22 which loosely embrace the opposite edges of the belt. The upper end of the arm 20 is furnished with a handle 23 by means of which the belt shifter may be moved manually.

The belt shifter also comprises the arm 24 which forms one element of a toggle device.

The other element of this toggle device consists of a rod 26 pivotally secured to the end of the arm 24 at the point 25 and guided at its opposite end in an opening in the lug 27 5 projecting upwardly from the frame 2. The rod 26 is free to slide and also to swing in the opening in the lug 27. A coiled spring 28 encircles the rod 26, bearing at one end against the lug 27 and at the other against 10 an enlargement or collar upon the rod adjacent to its pivotal connection to the arm 24. A shaft 28 is mounted in brackets 29 and 30 projecting from the rear of the frame 2. A split collar 31 is secured to the shaft 28 15 and a yarn-engaging detector plate 33 is secured to the split collar. A spring 34 encircles the shaft 28 and has one end 35 bearing against the under side of the frame 2 while its other end 36 bears against the 20 collar 31 and tends to swing the detector plate 33 against the winding yarn mass M. An arm 37 projects downwardly and forwardly from the collar 31 and has its forward end 38 disposed beneath the extreme 25 end of the arm 24 substantially at the point of connection of the latter to the rod 26.

A shaft 39 is journaled in an opening in the left-hand standard 2^a of the frame and a collar 39^a is secured to the end of this shaft 30 at the outer side of the standard 2^a. A detector 40 secured to the collar 39^a is preferably formed from bent wire and comprises the forwardly extending arm 41 and the transverse substantially horizontal arm 35 42 (Fig. 1). The arm 42 is substantially parallel to the axis of the winding spindle and is of a length to engage the yarn Y on its way to the winding mass in any position which it may be caused to assume by the 40 traverse mechanism.

A block 43 is secured to the shaft 39 below and in the plane of the pulley 5 and this block is furnished with a curved face 44 constituting a brake element engageable 45 with the peripheral surface of the pulley 5.

At its right-hand end the shaft 39 is furnished with a crank arm 45 to which the upper end of a link 46 is pivotally connected. The lower end of this link is furnished with 50 a forwardly extending toe 47 which is disposed adjacent to the forward end of the arm 37 and immediately below the end of the arm 24.

Pairs of grooved rolls 48 and 49 are 55 mounted at spaced intervals along the length of the winding frame, one pair of such rolls being shown as mounted upon the left-hand standard 2^a of the winding unit here illustrated. A traverse rod or bar 50 is mounted 60 between the rolls of the several pairs to reciprocate longitudinally of the machine. This bar 50 carries a slab removing yarn guide corresponding to each winding unit. Each of these yarn guides preferably 65 consists of a pair of plates 52 and 53 secured

in split collars 51 mounted upon the bar and spaced apart at their adjacent edges to provide a yarn guiding slot 54. This slot is of accurately uniform width from top to bottom so that regardless of the size of the winding yarn mass the yarn is properly guided and all slubs are detected and removed or the yarn is broken by their failure to pass the guide slot.

At suitable points brackets such as 55 are 75 secured to the table 1 and these brackets carry a yarn guiding rail 56 over which the yarn passes on its way from the yarn supply to the winding yarn mass. Preferably a stop device 57 is disposed above the connection between the arm 24 and the rod 26 to limit upward movement of the pivotal connection of these elements.

The device operates substantially as follows, it being assumed that the parts normally occupy the position indicated in the drawings. As thus arranged the yarn Y coming from the supply and suitably tensioned in any desired manner, as for example by frictionally retarding the supply 85 bobbin or spool, passes over the rail 56 and beneath the detector finger 42 whose weight is supported by the yarn and thence through the guide slot 54 to the yarn mass M. The detector plate 33 bears with light pressure 90 against the winding yarn mass. The belt shifter arm 20 is so disposed that the belt 18 engages the fast pulley 5 and the arm 24 of the belt shifter inclines downwardly and to the right as viewed in Fig. 2. As thus positioned, arm 24 and rod 26 are not in exact alignment but are disposed angularly with respect to each other and the parts are maintained in this position by means of the 100 spring 28.

As the yarn mass increases in diameter in the orderly operation of the machine, the plate 33 is gradually swung in a clockwise direction as viewed in Fig. 6 until the forward end 38 of the arm 37 engages the under side of the arm 24 whereupon the latter is lifted in opposition to the spring 28 until the arm 24 and the rod 26 pass a position of alignment whereupon the reaction of the spring 28^a 110 causes the toggle device comprising parts 24 and 26 to be broken and quickly swings the arm 20 to the left so as to carry the belt onto the loose pulley 6. The winding spindle is now stopped and the operator removes the 115 filled spool or yarn mass by swinging the bearing member 11 to the right. An empty spool can now be inserted and the winding operation resumed, the belt being replaced upon the fast pulley by manual operation of the handle 23 which at the same time restores the parts 24 and 26 to normal position.

If during the winding, the yarn should break or become unduly slack, the detector finger 42 which is supported by the yarn intermediate the rail 56 and the guide slot 130

54 is permitted to drop. This rocks the shaft 39 and swings the crank arm 45 so as to raise the link 46 to cause its toe 47 to engage the under side of the arm 24, 5 whereupon the toggle is broken in the same manner as above described and the belt is shifted onto the loose pulley. When the yarn breaks, it is particularly desirable to stop the spindle quickly and for this purpose the brake comprising the block 43 is provided. This brake is brought into engagement with the pulley 5 when the detector finger 42 drops so that immediately after the belt is shifted the spindle is brought to 10 rest.

The device above described is capable of winding yarn at very high speed and, as the detector devices is only called upon to overcome the resistance of the relatively 20 light spring 28^a, it may be made very light in weight, so that it will not injuriously strain the tenderest and finest yarns. The mechanism is extremely compact and easy to construct and is so easily manipulated 25 and certain in action that a single operator can care for a very large number of winding units.

I claim:

1. Winding mechanism comprising a rotary spindle, spindle driving means including a power transmission element movable to and from operative position, a toggle device controlling the position of the transmission element, and detector means determining the operation of the toggle device.

2. Winding mechanism comprising a power transmitter, a toggle device normally operative to hold the transmitter in operative position, a yarn detector normally supported by the winding yarn, and connections between the detector and the toggle device operative when the detector drops to actuate the toggle device and shift the transmitter to inoperative position.

3. Winding mechanism comprising a rotary spindle, drive means therefor including a power transmitter movable to and from operative position, a toggle device including pivotally connected members normally held in predetermined angular relation by a spring, means connecting one of the toggle members with the shifter, a yarn engaging detector, and means operable by the detector for changing the angular relation of the toggle members thereby to shift the transmitter to inoperative position.

4. Winding mechanism comprising a power transmitter, a toggle device connected thereto having pivotally connected elements normally occupying a predetermined angular relation to retain the transmitter in operative position, a pivoted detector finger normally supported by the yarn, a link having a part engageable with the toggle whereby to break the toggle to move the transmit-

ter to inoperative position, and means connecting the detector to the link to move the latter when the detector drops.

5. Winding mechanism comprising a rotary spindle, fast and loose pulleys thereon, a belt alternatively engageable with the respective pulleys, a belt shifter, a spring actuated toggle device constructed and arranged to retain the belt shifter in position to engage the belt with either of the pulleys, a yarn engaging detector, and connections between the detector and toggle mechanisms for transmitting movement from the former to the latter whereby to shift the belt.

6. Winding mechanism comprising a rotary spindle, drive means therefor including a power transmitter movable to and from operative position, a rocking shifter for the transmitter having a rigid arm constituting one element of a toggle device, a member pivotally connected to said arm constituting the other element of the toggle, a spring normally operative to hold the toggle elements in predetermined angular relation, a yarn engaging detector, and means operable by the detector for changing the angular relation of the toggle elements.

7. Winding mechanism comprising a rotating spindle, drive means therefor including a power transmitter movable to and from operative position, a shifter lever engaging the transmitter for moving the latter, said lever having an arm constituting one element of a toggle device, a rod hinged to said arm forming the other element of the toggle device, a guide for the opposite end of the rod, a spring tending to hold the toggle elements in predetermined angular relation, a yarn engaging detector, and means operable thereby to change the angular relation of the toggle elements.

8. Winding mechanism comprising a power transmitter, a toggle device controlling the transmitter, and a plurality of detector devices independently operative to actuate the toggle device to render the transmitter inoperative.

9. Winding mechanism comprising a power transmitter, a toggle device operative to maintain the transmitter in either operative or inoperative position, a plurality of yarn engaging detectors, and independent connections between the detectors and the toggle device to actuate the latter in accordance with movement of either detector.

10. Winding mechanism comprising a spindle, a power transmitter for driving it, a shaft substantially parallel to the spindle, a detector carried by the shaft actuatable by the winding yarn mass when the latter attains a predetermined diameter, means normally holding the detector in predetermined position but permitting it to be moved by the growing yarn mass, an arm secured to the shaft, and means engageable by the arm

upon movement of the detector for initiating movement of the power transmitter to inoperative position.

11. Winding mechanism comprising a frame, a spindle journaled therein, a power transmitter for driving the spindle, a lever pivotally supported upon the frame operatively connected to the transmitter, means normally holding the lever in predetermined position, a detector normally supported by the winding yarn, a detector engageable by the growing yarn mass when the latter attains a predetermined diameter, and members actuatable by the respective detectors to engage the lever for moving the latter in opposition to its spring.

12. Winding mechanism comprising a spindle, fast and loose pulleys mounted thereon, a belt engageable with either pulley, a belt shifter, a spring normally holding the belt shifter in position with the belt upon the fast pulley, a yarn break detector, a detector actuatable by the winding yarn mass when the latter attains a predetermined diameter, and members independently operable by the respective detectors for moving the belt shifter in opposition to the spring.

13. A winding machine comprising a spindle, a power transmitter for driving it, a bell crank lever having one arm operatively connected to the transmitter, a rod pivotally connected to the other arm of the lever and together therewith constituting a toggle device, a spring acting upon the toggle normally to maintain the power transmitter in driving position, a pivoted yarn break detector finger normally supported by the winding yarn, a crank arm movable by the finger, a link connected to the crank arm, a lug carried by the link engageable with the toggle device, a shaft substantially parallel with the spindle, a spring normally holding the shaft in predetermined position, a detector secured to the shaft arranged to be moved by the growing yarn mass upon the spindle, and an arm secured to the shaft having a part engageable with the toggle device.

14. A winding machine comprising a winding spindle, a reciprocable yarn traverse bar, a stationary guide rail, a slub detector carried by the bar having a yarn guiding slot, a detector finger normally supported by the yarn on its way from the guide rail to the guide slot upon the spindle, and spindle driving means including a power transmitter movable to inoperative position upon dropping of the detector.

15. A winding machine comprising a winding spindle, a reciprocable traverse member, a yarn guide carried thereby having a narrow guide slot for the passage of the yarn, a fixed guide rail over which the yarn passes on its way to the guide slot, a shaft substantially parallel to the spindle, a detector secured to the shaft having a yarn engaging portion extending substantially parallel to the spindle and between the guide rail and the guide slot, the yarn engaging portion normally resting upon and being supported by the winding yarn, and spindle driving means including a power transmitter movable to inoperative position when the detector drops.

16. Winding mechanism comprising a winding spindle, a detector device, and a brake operable by the detector for retarding the rotation of the spindle.

17. Winding mechanism comprising a winding spindle, a power transmitter therefor, a detector device for initiating movement of the transmitter to inoperative position, and a brake actuated by the detector for bringing the spindle to rest.

18. Winding mechanism comprising a winding spindle, having fast and loose pulleys thereon, a driving belt, a belt shifter, a detector for initiating movement of the belt shifter to shift the belt from the fast to the loose pulley, and a brake movable by the detector engageable with the fast pulley to bring the spindle to rest after shifting of the belt.

Signed by me at Boston, Massachusetts, this seventh day of September, 1928.

ANKER PETERSEN.
